Filed Nov. 7, 1960, Ser. No. 67,529
12 Claims. (Cl. 315—135)

This invention relates to low voltage indicating lights and more particularly to an improved low voltage indicator light utilizing a neon bulb.

Indicator lights have been well known and used in connection with electrical equipment both for signal indication purposes and for indicating various conditions of operation of electrical equipment. On low voltage applications, and in particular in connection with direct current power supplies or signal sources, the indication lamp required would be of the incandescent type and would normally present a certain power drain to the associated equipment. This type of apparatus normally has limited life and requires regular maintenance. Neon indication lamps are normally restricted to high voltage alternating current or direct current applications since high voltage types of power supplies are necessary to fire or energize the neon bulb. Such an indicator type does, however, have the desirability of low current drain and long life, eliminating maintenance problems and increasing reliability in operation. Where this type of indicating light is applied to low voltage direct current battery type power supplies, it has always required rather complex and expensive power conversion equipment to operate the lamp.

The present invention is directed to an improved indicating light or lamp which includes as part thereof power conversion equipment to provide a complete self-contained indicating unit suitable for application to low voltage direct current power supplies. It is therefore an object of this invention to provide an improved indicating light for direct current low voltage equipment.

Another object of this invention is to provide an indicating light which is small and compact and has an exceptionally long life and low current drain.

A further object of this invention is to provide an improved indicating light which utilizes circuitry permitting the use of a neon bulb to give long life and which is applicable to low voltage operation.

Another object of this invention is to provide an indicating light of this type which may be operated by signal sources a part of the energization thereof.

It is also an object of this invention to provide in an indicating light of this type improved circuitry to prevent overheating of the transistor oscillator.

These and other objects of this invention will become apparent from the reading of the attached description together with the drawings wherein:

FIG. 1 is a plan view of the improved indicator light,

FIG. 2 is a plan view of the indicator light with the casing removed to disclose the arrangement of parts,

FIG. 3 is a bottom view of the indicator light of FIG. 2 showing the circuit conductors,

FIG. 4 is a schematic circuit of one embodiment of the improved indicator light,

FIG. 5 is a schematic circuit of the second embodiment of the improved indicator light.

Our improved indicator light is shown in plan view in FIG. 1 as including an opaque casing 10 which is cylindrical in form and has a reduced diameter portion 12 which is threaded as at 13 with a clear or transparent closed end tip 15 integral therewith or suitably secured thereto. The casing is open at its opposite extremity and normally has a securing nut 20 on the threaded por-

2

tion 13 designed to clamp the lamp into an aperture in the enclosure or panel of the device (not shown) upon which the indicating lamp is to be mounted. Extending from the open end of the casing are a plurality of terminals 21, 22 by means of which a power supply may be connected to the indicating light. Two such terminals are shown in FIG. 1 to indicate one embodiment or version of the indicating lamp while in FIGS. 2 and 3 a third terminal is included, indicated as 24, to indicate a second circuit embodiment of the lamp.

FIGS. 2 and 3 show the indicating lamp with the cover or casing 10 removed to disclose the arrangement and connection of parts. It will be seen in FIG. 2 that the parts are all mounted on a supporting base or support structure, indicated at 25, which is made of insulating material, such as a suitable plastic. Base 25 is rectangular in form and extends along the extent of the casing 10. Positioned at one extremity of the base or support 25 is an insulating disc or terminal support 26 in which the terminals 21, 22, and 24 are positioned, the disc being held in position relative to the support through suitable means such as the electrical connections between the terminals and parts, or if desired, through mechanical connecting means. In FIG. 2 the terminals extend through the disc and are connected directly to a plurality of resistor elements indicated generally at 30 which will be later specifically identified in connection with the circuit. It has been found that sufficient strength and rigidity exists between the electrical connections of the resistors 30 to the terminals and to the board to provide strength of mounting of the disc 26 to the support or base 25 eliminating further mechanical connections therebetween. The disc 26 is of sufficient diametrical dimension to fill the open end of the casing 10 and would be normally secured thereto through suitable sealing means (not shown).

Also included on the support and suitably secured thereto are a transistor indicated generally at 32, a core indicated at 35 which is connected to the board through a suitable means indicated at 36, a condenser indicated at 37, a resistor indicated at 38, and a neon glow bulb 40 which is connected through its electrodes to the base member 25 and is positioned to extend along the axis of the support.

As will be seen in FIG. 1 when the support with the transistor, core and bulb together with the associated resistors and condensers are positioned within the casing 10, the bulb will be located adjacent the transparent portion 15 of the casing to provide for indication from the bulb.

The bottom view of the support, as shown in FIG. 3, discloses circuit conductors indicated generally at 45, between the various elements mounted on the upper surface of the board, these conductors being printed on or suitably connected to the support to be integral therewith. The solder connections between the conductors and the resistors, as well as the various other elements of the circuits, provide a complete electrical circuit as well as mechanical connection between the parts. As will be later seen the core 35 encloses and houses an inductance coil and a transformer winding which make up the oscillator portion of the circuitry for the indicating lamp.

In FIG. 4 an embodiment of the indicating light is shown which is suitable for application directly to a low voltage power supply, for indication of power on or power off without auxiliary control. In this embodiment of the apparatus, the transistor 32 is of the PNP type, and the power supply can be either a negative or positive polarity direct current of approximately 12 to 24 volts. This embodiment of the indicator light includes a first circuit extending from terminal 21 through a conductor 50, a conductor 51 to a portion 52 of a winding 53 and from a tap

55 on the winding through a conductor 56 to a collector electrode 58 of transistor 32. The circuit is completed by connection of an emitter electrode 60 of transistor 32 to an inductance coil 61, a resistor 62, a conductor 63, and terminal 22. The windings or coils 53 and 61 are mounted within the core 35 and are common thereto with the portion 52 of the winding 53 forming the primary of an auto transformer circuit, to be later identified. This circuit which includes the transistor, the inductance coil 61 and coil portion 52 with the core 35 and resistor 62 provides a blocking oscillator type circuit. A second circuit for the oscillator extends from terminal 21 through a conductor 64, a bias resistor 65, and a conductor 66 to a base electrode 67 of transistor 32 for biasing purposes. A diode 70 is connected between conductors 66 and conductor 63 or around the resistor 62, coil 61 and transistor 32 to provide a bleed path or low impedance shunt around the transistor to prevent thermal overload or overheating of the transistor, as will be more fully described below. The resistors 62, 65 and the diode 70 are all part of the combination of resistor elements indicated generally at 30 in FIG. 1. The neon glow bulb 40 is energized from the circuit connected to the extremities of the winding 53 through conductors 51 and 75, this circuit including the current limiting resistor 38, with the condenser 37 connected in parallel with the bulb 40 and resistor 38 for voltage smoothing purposes. This energizing circuit for bulb 40 provides a step-up auto transformer type connection to generate the high voltage from the oscillation of the transistor oscillator sufficient to fire the neon bulb and maintain it ignited or energized with oscillation from the transistor oscillator. While we have shown an auto transformer connection from the output of the transistor oscillator, it will be recognized that a conventional transformer circuit may be utilized with the indicating bulb connected directly to a secondary winding and with a primary winding included on a common core with the inductance to provide a blocking oscillator type circuit.

In operation the indicator light may be connected across a negative polarity power supply, in which case the terminal 22 will be grounded and the terminal 21 will be connected to the negative supply, or the circuit may be connected to a positive polarity supply in which case the terminal 22 will be connected to a positive supply and the terminal 21 will be grounded. With direct current applied to the terminals 21, 22, the first named circuit will provide for pulsed current flow through the primary portion of the auto transformer due to oscillation of the blocking oscillator type circuitry to cause a step up in voltage across the entire or secondary portion of the auto transformer sufficient to ignite or fire the indicating light. With the blocking oscillator circuit, the common core saturates as the transistor conduits. The transistor oscillator first turn on because of its energization with the bias across the resistor 65. As the common core reaches saturation with current flow through the transistor, the rate of change of current flow in the inductance coil begins to decrease and begins to turn off the transistor. As current flow drops to zero through the inductance, the bias on the base of the transistor will cause a change in polarity turning on the transistor again. This operation of the blocking oscillator is conventional, and the pulsed current flow through the primary portion of the auto transformer represents the output flow therefrom. The diode 70 connected across the transistor and inductor provides a current bleed in a direction to prevent the current flow through the transistor from becoming too high and overheating the transistor.

This apparatus is a self contained current conversion and voltage step-up device which permits the use of a low voltage direct current source to operate a neon bulb where direct connection to the source would not operate the bulb. It further permits the use of a neon bulb with its inherent low current drain and long life to provide a satisfactory and desirable indicating lamp. The power

5 consumption from this apparatus is in the milliwatt range, thereby permitting it to be utilized with battery operated power supplies without significant power consumption for indication purposes. Further, no associated electrical equipment is required in a power supply equipment to operate the indicator lamp.

The embodiment of the indicator light shown in FIG. 5 is substantially the same shown in FIG. 4 with the additional provision for a third terminal 24 as a means by which a control signal may be applied to the transistor oscillator to cause the same to fire or ignite the indicator light under one set of signal conditions and to turn the lamp off under a second set of signal conditions. Thus FIG. 5 shows the main power circuit or output circuit to extend from terminal 21 through the conductors 50, 51 to the primary portion 52 of transformer 53 and from the conductor 56 to the collector electrode 58 of transistor 32. The circuit is completed from the emitter electrode 60 through the inductance 61, resistance 62 to a conductor 63 and terminal 22. This circuit utilizes an NPN type transistor with terminal 21 connected to a positive polarity side of the battery or supply ranging from 12 to 24 volts and with terminal 22 grounded. The secondary portion of the transformer, that is the extremities of the winding 53, are connected through the conductors 51 and 75 to the resistor 38 and bulb 40 with the condenser 37 connected in parallel therewith.

This embodiment also utilizes the common core 35 between the transformer winding and the inductance and, as in the before mentioned embodiment, a separate secondary winding may be incorporated or utilized in a conventional transformer configuration if desired. The circuitry shown, provides an auto transformer type connection between the primary portion 52 and the entire windings 53 to provide a step-up transformer for firing the indicator bulb 40. A bias circuit is also included from the terminal 21 through the conductor 64 and resistor 65 to the base electrode 67 of the transistor. Diode 70 is connected between the base electrode and the conductor 63, and it is poled for an opposite direction of current flow because of the different type of transistor. The diode circuit, as in the first embodiment, provides a bleed path from the base electrode of the transistor shunting the inductance and resistor to prevent overheating of the transistor by limiting current flow therethrough.

A signal circuit is provided in this embodiment from the electrode 24 through a conductor 80, a bias resistor 85 to the base electrode 67 of the transistor. This signal circuit is adapted to be energized with a positive polarity signal of approximately 0 to 6 volts to turn the bulb on and with a negative polarity signal of 4 to 10 volts to turn the light off, when the power supply is approximately 24 volts D.C. The electrical components, that is the inductance and resistors, together with the transistor, are so chosen that with energization across the terminals 21, 22, and no energization on the circuit from terminal 24 the transistor oscillator circuit will start to oscillate and fire the bulb to provide an indication. A positive signal applied to the terminal 24, or across the bias resistor 85, will hold the light in an energized condition. This additional bias current acts together with the bias circuit through resistor 65 to bias the base electrode such that the transistor will go into oscillation in a conventional blocking oscillator type of operation. When a negative polarity signal is applied to terminal 24 it lowers the bias on the base and the transistor will not go into oscillation and will maintain the light deenergized.

In this embodiment, the oscillator still operates as a blocking oscillator with a common core between the transformer and inductance windings, which core goes into saturation decreasing current flow through the inductance. The bias circuits including the circuits through the resistor 65 and the signal bias resistor 85 connected to the base electrode provide the bias causing the oscillator to

connecting said transformer winding across a second resistor and said glow bulb; third circuit means including a third resistor connected to said one of said terminals and the base electrode of said transistor to provide a biasing circuit for said oscillator circuit, fourth circuit means including a diode connected between said transistor base electrode and said first resistor; said first, second, third and fourth circuits including conductors positioned on and included as a part of said support; and casing means having a transparent closed extremity, said casing means being mounted to enclose said support with said bulb positioned adjacent said transparent extremity and joined to said disc.

6. In an indicator light, an elongated support, a transistor having collector, emitter and base electrodes and mounted on said support; a transformer winding and an inductance enclosed by a common core and connected to said support; a glow bulb mounted on said support at one extremity thereof and extending along the axis of said support, disc means including a plurality of terminals mounted on the other end of said support; first circuit means extending from one of said terminals through a portion of said transformer winding to the collector electrode of said transistor and from the emitter electrode through a first resistor and said inductance to another of said terminals to provide an oscillator circuit adapted to be connected to a source of power; second circuit means connecting said transformer winding across a second resistor and said glow bulb; third circuit means including a third resistor connected to said one of said terminals and the base electrode of said transistor to provide a biasing circuit for said oscillator circuit; fourth circuit means including a diode connected between said transistor base electrode and said first resistor; fifth circuit means connected from a third of said terminals through a bias resistor to said base electrode and operative when energized with a predetermined electrical signal to turn on and off said light; said first, second, third, fourth and fifth circuits including conductors positioned on and included in part of said support; and casing means being mounted to enclose said support with said bulb positioned adjacent at transparent extremity and said casing means joined to said disc means.

7. In an indicator light, a transistor including an emitter, collector and base electrodes; a transformer winding and an inductance winding positioned within and enclosed by a common core, a glow bulb, first circuit means including terminal means connected through a portion of said transformer winding to the collector electrode of said transistor and from the emitter electrode through a first resistor and said inductance to provide a blocking oscillator circuit adapted to be connected to a source of power; second circuit means connecting said transformer winding across a second resistor and said glow bulb; third circuit means including a third resistor connected to one of said terminal means and the base electrode of said transistor to provide a biasing circuit for said oscillator circuit; and fourth circuit means including a diode connected between said transistor base electrode and said first resistor to provide a low impedance circuit around said transistor and said inductance winding.

8. In an indicator light: an elongated support, a transistor including emitter, collector and base electrodes mounted on said support; a transformer winding and an inductance winding magnetically associated with a common core mounted on said support; a neon bulb mounted on said support and extending along the axis of said support; terminal means including a plurality of terminals mounted on the other end of said support; first circuit means extending from one of said terminals through a portion of said transformer winding to the collector electrode of said transistor and from the emitter electrode through a first resistor and said inductance to another of said terminals to provide a blocking oscillator circuit adapted to be connected to a source of power; second circuit means

connecting said transformer winding across a second resistor and said neon bulb; third circuit means including a third resistor connected to said one of said terminals and the base electrode of said transistor to provide a biasing circuit for said oscillator circuit, and fourth circuit means including a diode connected between said transistor base electrode and said first named resistor.

9. In an indicator light, a transistor including emitter, collector and base electrodes; a transformer winding and an inductance winding positioned within and enclosed by a common core, a glow bulb, first circuit means including terminal means connected through a portion of said transformer winding to the collector electrode of said transistor and from the emitter electrode through a first resistor and said inductance to provide a blocking oscillator circuit adapted to be connected to a source of power; second circuit means connecting said transformer winding across a second resistor and said glow bulb; third circuit means including a third resistor connected to one of said terminal means and the base electrode of said transistor to provide a biasing circuit for said oscillator circuit; fourth circuit means including a diode connected between said transistor base electrode and said first resistor to provide a low impedance circuit around said transistor and said inductance winding, fifth circuit means connected from a third of said terminals through a bias resistor to said base electrode and operative when energized with a predetermined electrical signal to turn on and off said bulb.

10. In an indicator light, a transistor including emitter collector and base electrodes; a transformer winding and an inductance winding magnetically associated with a common core, a glow bulb, first circuit means including terminal means connected through a primary portion of said transformer winding to the collector electrode of said transistor and from the emitter electrode through a first resistor and said inductance to provide a blocking oscillator circuit adapted to be connected to a source of power; second circuit means connecting a second portion of said transformer winding to said glow bulb; third circuit means including a second resistor connected to one of said terminal means and the base electrode of said transistor to provide a biasing circuit for said oscillator circuit; fourth circuit means including a diode connected between said transistor base electrode and said first resistor to provide a low impedance circuit around said transistor and said inductance winding.

11. In an indicator light, an elongated support, a transistor including emitter, collector and base electrodes mounted on said support, a winding and an inductance coil magnetically associated with a common core on said support, a glow bulb mounted on said support at one extremity thereof, terminal means including a plurality of terminals mounted on the other end of said support, first circuit means extending from a first of said terminals through a portion of said winding to the collector electrode of said transistor and from the emitter electrode through a first resistor and said inductance coil to another of said terminals to provide an oscillator circuit adapted to be connected to a source of power, second circuit means connecting said winding to said glow bulb in a step up transformer circuit, third circuit means including a bias resistor connected to said first terminal and the base electrode of said transistor to provide a biasing circuit for said oscillator circuit, and fourth circuit means including a diode connected between said transistor base electrode and said first resistor.

12. In an indicator light: an elongated support, a transistor including emitter, collector and base electrodes mounted on said support; a transformer winding and an inductance winding magnetically associated with a common core mounted on said support; a neon bulb mounted on said support and extending along the axis of said support; terminal means including a plurality of terminals mounted on the other end of said support; first circuit

turn on again. This will cause a current output through the primary portion of the auto transformer to provide a step-up voltage sufficient to fire or ignite the indicator light 40. The condenser 37 filters and smooths current flow through the neon bulb to provide a voltage to maintain the bulb 40 ignited or energized. Diode 70 is connected around the inductance 61, resistor 62 and a portion of the transistor to provide a bleed path to limit current flow in the transistor and prevent overheating of the same, thereby improving the life of the apparatus. This circuit embodiment permits control of the indicator light from an auxiliary high impedance signal. Further, the output of the auto transformer is fed through the filtering circuit sufficient to maintain a high indication or glow of the neon bulb.

It will be seen that our improved indicator light includes a self-contained current converter or modulator permitting the indicator light to be operated from a direct current source and including further a step up transformer to provide sufficiently high voltage to ignite a neon type bulb from a low voltage source. The apparatus is all mounted on a printed circuit base with a terminal assembly connected thereto such that it may be housed in a casing with the bulb positioned adjacent to a portion of the casing to give indication therethrough.

It will be recognized that certain changes may be made in the shape and type of its components, and hence we wish our invention to be limited only by the scope of the appended claims.

What is claimed is:

1. In an indicator light: an elongated support, a transistor including emitter, collector and base electrodes mounted on said support; a transformer winding and an inductance winding positioned within and enclosed by a common core connected to said support; a neon bulb mounted on said support and extending along the axis of said support; terminal means including a plurality of terminals mounted on the other end of said support; first circuit means extending from one of said terminals through a portion of said transformer winding to the collector electrode of said transistor and from the emitter electrode through a first resistor and said inductance to another of said terminals to provide a blocking oscillator circuit adapted to be connected to a source of power; second circuit means connecting said transformer winding across a second resistor and said neon bulb; third circuit means including a third resistor connected to said one of said terminals and the base electrode of said transistor to provide a biasing circuit for said oscillator circuit; fourth circuit means including a diode connected between said transistor base electrode and said first named resistor; said first, second, third and fourth circuits including conductors printed on said support; and casing means having an opaque body with a transparent closed extremity fitted over said support such that said bulb is positioned adjacent said transparent extremity and the casing joins the said terminal means to enclose said light.

2. In an indicator light, an elongated support, a transistor mounted on said support, an auto transformer winding and an inductance winding positioned within and enclosed by a common core connected to said support, a neon bulb mounted on said support and extending along the axis of said support, an annular terminal support including a plurality of terminals mounted on the other end of said support, a first circuit means extending from one of said terminals through the primary portion of said auto-transformer winding to the collector electrode of said transistor and from the emitter electrode through a first resistor and said inductance to another of said terminals to provide a blocking oscillator circuit adapted to be connected to a source of power; second circuit means connecting the secondary portion of said auto transformer winding across a second resistor and said neon bulb, third circuit means including a third resistor connected to said first terminal and the base electrode of said transistor to

provide a biasing circuit for said oscillator circuit, fourth circuit means including a diode connected between said transistor base electrode and said first resistor, said first, second, third and fourth circuits including conductors printed on said support, and cylindrical casing means having an opaque body with a transparent closed extremity fitted over said support such that said bulb is positioned adjacent said transparent extremity and the casing is joined with the said terminal support to enclose said light.

10 3. In an indicator light, an elongated support, a transistor including emitter, collector and base electrodes mounted on said support, a winding and an inductance coil positioned within a common core and mounted on said support, a glow bulb mounted on said support at one extremity thereof, circular terminal means including a plurality of terminals mounted on the other end of said support, first circuit means extending from a first of said terminals through a portion of said winding to the collector electrode of said transistor and from the emitter 15 electrode through a first resistor and said inductance coil to another of said terminals to provide an oscillator circuit adapted to be connected to a source of power, second circuit means connecting said winding across a second resistor and said glow bulb in a step up transformer circuit, third circuit means including a third resistor connected to said first terminal and the base electrode of said transistor to provide a biasing circuit for said oscillator circuit, fourth circuit means including a diode connected between said transistor base electrode and said first resistor, said first, second, third and fourth circuits including conductors integral with said support, and means encasing said support having an opaque body with a transparent extremity such that said bulb is positioned adjacent said transparent extremity and the encasing means is joined to the said terminal means to enclose said light.

20 4. In an indicator light, an elongated support, a transistor including emitter, collector and base electrode mounted on said support, a tapped winding and an inductance winding associated with a common core connected to said support, a glow bulb mounted on said support at one extremity thereof, terminal means including a plurality of terminals mounted on the other end of said support, first circuit means extending from one of said terminals through a portion of said tapped winding to the collector electrode of said transistor and from the emitter electrode through a first resistor and said inductance to another of said terminals to provide an oscillator circuit adapted to be connected to a source of power, second circuit means connecting said entire tapped winding across a second resistor and said glow bulb, third circuit means including a third resistor connected to said one of said terminals and the base electrode of said transistor to provide a biasing circuit for said oscillator circuit, fourth circuit means including a diode connected between said transistor base electrode and said first resistor, said first, second, third and fourth circuits including conductors integral with said support, and means encasing said support having an opaque body with a transparent extremity with said bulb positioned adjacent said transparent extremity and the encasing means joined to the said terminal means to enclose said light.

25 5. In an indicator light, an elongated support; a transistor having collector, emitter and base electrodes mounted on said support; a transformer winding and an inductance enclosed on a common core and connected to said support; a glow bulb mounted on said support at one extremity thereof and extending along the axis of said support; disc means including a plurality of terminals mounted on the other end of said support; first circuit means extending from one of said terminals through a portion of said transformer winding to the collector electrode of said transistor and from the emitter electrode through a first resistor and said inductance to another of said terminals to provide an oscillator circuit adapted to be connected to a source of power; second circuit means

means extending from one of said terminals through a portion of said transformer winding to the collector electrode of said transistor and from the emitter electrode through a first resistor and inductance to another of said terminals to provide a blocking oscillator circuit adapted to be connected to a source of power; second circuit means connecting said transformer winding across a second resistor and said neon bulb; third circuit means including a third resistor connected to said one of said terminals and the base electrode of said transistor to 10 provide a biasing circuit for said oscillator circuit and

fourth circuit means including a unidirectional variable impedance circuit element connected between said transistor base electrode and said first named resistor.
